UNITED STATES PATENT OFFICE.

JOHN R. HIRSH, OF SYRACUSE, NEW YORK.

DESIGN FOR A HAT-HOOK.

SPECIFICATION forming part of Design No. 25,506, dated May 19, 1896.

Application filed April 18, 1896. Serial No. 588,189. Term of patent 7 years.

To all whom it may concern:

Be it known that I, JOHN R. HIRSH, of Syracuse, in the county of Onondaga, in the State of New York, have invented a new and original Design for Hat-Hooks, of which the following, taken in connection with the accompanying drawings, is a full, clear, and exact description.

Figure 1 is a top plan view of my design for a hat-hook. Fig. 2 is an edge view thereof, these two views being deemed necessary to properly illustrate the design.

The leading feature of my design consists in a base, rectangular at one end, and merges gradually into an enlargement near the opposite end, terminating in a rectangle, which merges into the top or the clamp, which top or clamp at one end is circular in form and terminates in a narrow tongue, the outer end 20 of which is turned downward until it engages with the rectangular basis, and this turns upward.

a is the base. *b* is the rectangular end thereof. *c* is the opposite end, which terminates in the rectangular end *d*. *e* is one end of the clamp, and *f* is the tongue, *g* being the curve near the end. The irregular outline of the base and clamp complete when viewed from the top in contrast with the symmetrical contour when viewed from the edge presents 30 a pleasing effect to the eye.

Having described my invention, what I desire to secure by Letters Patent is—

The design for a hat-hook substantially as herein described and shown. 35

In witness whereof I have hereunto set my hand this 14th day of April, 1896.

JOHN R. HIRSH.

In presence of—

HOWARD P. DENISON,
MAUDE E. COOKE.
